UNITED STATES PATENT OFFICE.

JAMES LEWIS KIMBALL, OF SALEM, MASSACHUSETTS, ASSIGNOR TO RUGGLES-KLINGE-MANN MFG. CO., OF SALEM, MASSACHUSETTS, A CORPORATION OF MASSACHUSETTS.

DAMPER REGULATOR.

Application filed January 8, 1923. Serial No. 611,390.

To all whom it may concern:

Be it known that I, JAMES LEWIS KIMBALL, a citizen of the United States, residing at 9 Dearborn St., Salem, in the county of Essex and State of Massachusetts, have invented certain new and useful Improvements in Damper Regulators, of which the following is a specification.

This invention relates to damper regulators for controlling the air supply to boiler furnaces from variations of steam pressure generated by said boilers, and particularly to improved means for variably compensating the movement of such regulators from the flue gas pressure.

My invention is a further development of the present art as in this invention I substitute flue gas pressure for mechanical means for variably compensating the action of a regulator which is controlled primarily from steam pressure.

The object of this invention is to automatically correct a condition of furnace inefficiency due to the volume of gases generated in the boiler furnace not being consistent with the load on the boiler as indicated by the steam pressure, and to provide means whereby the variation in flue gas pressure may reverse or nullify the action of the damper regulator as controlled from the steam pressure, but to provide certain limits in pressure under which the control of the damper will be placed under the control of the steam pressure regardless of the furnace conditions, or the volume of gases being discharged to the stack or chimney. It will be understood that where mechanical means is provided for variably governing the movement of the flue damper, the compensating effect will not always be applied at the proper point to check the draft, under light load conditions or when only a few of the total number of boilers are in use the damper is to be closed to a greater extent before a grip is obtained on the draft than what would be the case when the load was heavy and all the boilers were in use.

In my invention an increase in steam pressure on a falling load will allow the damper to be freely closed to a point where it commences to check the draft, and this point will be reached sooner with a heavy furnace fire with a large volume of gases being discharged to the stack, than with a light fuel

bed, and from the point where the regulator commences to check the draft to a closed damper position, an increasingly counteracting force is applied to the regulator. From its working position where it commences to check the draft any increase or decrease in the volume of gases generated will move the damper, and increase in gases slightly opening the damper and a decrease slightly closing the damper, although the steam pressure in both cases remaining at a fixed value. This independent action of the damper from flue gas pressure operates to correct a condition of insufficient or an excess of air. In the first case it corrects an otherwise deficiency of air passing through the fuel bed which would result in unburned gases and in the second case we avoid an excess of air passing through the furnace with corresponding losses due to excess heat in the flue gases.

A clear conception of my invention may be had by reference to the drawings accompanying and forming a part of the specifications, in which like reference characters designate the same or similar parts in the several views.

Fig. 1 shows the application of my invention to a main flue damper of two steam boilers. Fig. 2 shows a vertical section of my invention in which the weight levers of the steam pressure chamber and the flue gas pressure chamber are connected together. Fig. 3 represents an embodiment of my invention in which the weight levers of both the steam pressure chamber and flue gas pressure chamber operate directly on the controlling valve.

Referring to Fig. 1. The steam boilers are represented by (1), and (2). (3) is the main flue, (4) the stack of chimney, (5) is the steam discharge pipe from the boilers, (6) is the main flue damper, (7) is a fluid pressure motor for operating the damper, the action being that when fluid pressure is admitted to the bottom of the motor, it raises weights (8) and allows weight (9) to close damper, and when fluid pressure is exhausted from motor (7), it allows weights (8) to become effective and overcome weight (9) and open damper. (10) is a flue gas connection to pressure chamber (11), (12) is a steam pressure connection to pressure chamber (13). Pres-

sure chambers (13) and (11) are closed by flexible diaphragms (14) and (15), weight lever (16) is fulcrumed at (17), a pressure cap (18) is in contact with the atmospheric side of diaphragm (14) and engages weight lever (16) at point (19). The steam pressure in chamber (13) is counteracted by weights (20) placed on weight lever (16). Variation in pressure in chamber (13) operates controlling valve (21) through connection (22) controlling valve (21) has inlet for fluid pressure at (23), delivering to fluid pressure motor at (24) and exhaust at (25). The negative gas pressure acting in chamber (11) is counteracted by weights (26), the weight lever (27) being fulcrumed at (28), a connection (29) being made between the left hand end of scale beam (27) and arm (30) which is fulcrumed to weight lever (16) at point (22). The right hand end of arm (30) is connected with operating valve yoke (31) which controls the admission and exhaust of fluid pressure to fluid pressure motor (7). A clearer conception of the operation of this valve will be had by referring to Figs. 2 and 3. It will be seen that the yoke (31) is connected to valve stem (32), valve stem (32) having cylindrical portions (33) which controls the admission and exhaust of fluid pressure to motor (7), when the stem is raised the pressure from connection (23) is admitted to connection (24), and when the stem is lowered, this pressure is closed off and the pressure in connection (24) is discharged through exhaust connection (25). The two pressure devices that, are acted upon by the pressure, are each balanced by counteracting weights placed on the weight levers, and each act independently of one another, to operate the controlling valve to actuate the fluid pressure motor to open and close the main damper.

We will now explain the operation of the regulator from steam pressure. An increase in steam pressure is communicated through pipe (12) to diaphragm chamber (13) which forces pressure cap (18) downward and as weight lever (16) is fulcrumed at (17) point (22) to which arm (30) is pivoted will be raised and as the left hand end of arm (30) for the time being is held stationary by connection (29), it will be apparent that the right hand end of arm (30) will be raised with scale beam (16), and as yoke (31) is connected to the right hand end of arm (30) and the upper end of the yoke connected to valve stem (32), it will be seen that the controlling valve will admit fluid pressure to the motor cylinder (7) and force piston (34) upward closing the damper and as the boiler pressure is reduced the balancing weights (20) will overcome the pressure in chamber (13)

and weight lever (16) will be moved downward closing the admission of pressure to the operating cylinder and opening the same to exhaust, causing piston (34) to be forced downward by weight (8) and opening the damper.

The operation thus far explained would be of the non-floating form, the damper would be opened and closed with only slight variation in steam pressure. We will now explain the operation from flue gas pressure and show how the regulator operated from steam pressure is compensated and becomes a variable floating device from the action of the flue gas pressure. The gas pressure in the main flue is usually negative to the amount of the chimney action, but may be increased to zero or even become positive at times. The variation in pressure being due to the volume of gases being generated in the boiler furnace or to the position of the main damper. Assuming a fresh charge of coal to be placed in the furnace, the increased volume of gases will reduce the negative pressure and this reduction of negative pressure acting in chamber (11) will allow weights (26) to overcome the atmospheric pressure as exerted on the top of diaphragm (15) and diaphragm (15) will be raised, this movement of the diaphragm acting through connection (29) and arm (30) will give a downward movement to yoke (31) and valve stem (32) which will exhaust fluid pressure from cylinder (7) and slightly open damper. The reason why damper is not opened wide is that as the damper starts to open, the negative pressure in the boiler flue is increased by the chimney action and this change in pressure acting through pipe (10) allows the atmospheric pressure to overcome weights (26) and the controlling valve is at once moved from an exhaust position to a neutral position. Assuming that the fuel in the boiler furnace has burned down so that the volume of escaping gases is materially lessened then the suction in the main flue is increased by increased chimney action, and this increased vacuum or negative pressure acting in chamber (11) will allow the atmospheric pressure to force diaphragm (15) downward which will operate motor piston (34) on the upward stroke slightly closing damper, which closing reduces the negative pressure and checks the further closing of the damper. From the above it will be seen that the fluid pressure motor can be operated independently from either variations in flue gas pressure or from variations in steam pressure.

We will now explain the compensating effect, the flue gas has on the regulator when operated from steam pressure. On an increase in steam pressure the damper

is closed to a position where it commences to check the draft, and as the closing of the damper commences to reduce the negative pressure in the boiler flue, the change in pressure is communicated to diaphragm chamber (11) which allows weights (26) to overcome the pressure of the atmosphere moving the diaphragm upward and controlling valve stem downward which movement is in the opposite direction to what the valve is being moved by the steam pressure. The further the steam pressure closes the damper the less the negative pressure becomes and the more the gas regulator tries to open it. This conflict is continued for a certain range in pressure then the steam pressure device overcomes the gas device and the motor is moved to close the damper and prevent a further rise in pressure. On a decrease in steam pressure, the steam device will operate the controlling valve to open damper and the increase in negative pressure due to the opening of the damper will act to return the controlling valve to a neutral position checking the further opening until a further drop in steam pressure takes place. This conflict of pressure devices is continued until the damper is opened to a position where maximum draft is obtained and from this point to a wide open position the damper is freely moved without compensating effect.

Referring to Fig. 2, we show a slight modification from what is shown in Fig. 3. While Fig. 3 shows an arrangement whereby the controlling valve is operated from either variations in flue gas pressure or variations in steam pressure, the arrangement in Fig. 2 permits variation in flue gas pressure to counteract the operation of the controlling valve as operated from steam pressure, the effect in both cases is the same.

In the ordinary draft regulator with mechanical means for compensating its movement, the regulator will commence to compensate in closing off the draft from its first movement, and will compensate the same for light loads as for heavy loads, but with my invention no compensating action takes place until the damper reaches a position where it commences to get a grip on the draft. The benefit of such a device is that it at once on a change of pressure swings the damper to a position where it commences to regulate the draft, and the two extremes of excess air on one hand and insufficient air on the other is avoided, and this permits me to operate boilers at low ratings nearly as efficient as at maximum efficiency ratings. It also permits me to operate boilers at a much smaller pressure operating range between minimum and maximum air supply than what was formerly required. With my invention the draft

regulator becomes self compensating and compensates at the point where incremental action is required, and will not compensate at the other points where no compensating action is required.

In case of a single boiler when the load is light and the fuel bed is thin, the same amount of damper opening for a given drop in pressure is not required, as would be the case if the load was heavy and it was necessary to maintain a thicker fuel bed. With my invention the steam pressure places limitations on the movement of the damper beyond which the damper must be entirely closed or entirely open, but between these limits the position of the damper may be changed from flue gas pressure to correction variation in load or furnace conditions, where such variations have not affected the steam pressure.

I am well aware of the fact that others have devised means for limiting the action of a flue gas or furnace pressure regulator from the steam pressure of the boiler, but in such regulators (and I refer to Parker #575,849 of January 26, 1897, and T. Niell #526,510 of September 25, 1894) the damper is controlled primarily from flue gas or furnace pressure and the steam pressure device is used to block or limit the movement of the gas regulator. In my invention the damper is moved primarily from steam pressure and the flue gas is used to variably compensate its action in accordance with the rate of combustion.

It will be understood by those skilled in the art that I have devised novel and satisfactory means for correcting defects in damper regulation, when such regulation is effected solely from steam pressure, and it is to be understood that the various instrumentalities of which my invention consists can be variously arranged and organized without departing from the scope of the invention. I therefore, desire only such limitations as are set forth in the appending claims.

I claim:

1. In combination with a plurality of steam boilers, a main draft flue for said boilers, a damper in said flue, a chimney or stack for creating a draft in the flue for discharging the gases generated in the furnaces of said boilers, means for operating said damper from variations in steam pressure generated by said boilers, and means for compensating the movement of said damper operating means from variations in draft caused by the movement of the damper from variations in steam pressure.

2. In combination with a flue damper for controlling the discharge of gases generated in the furnace of a steam boiler, a motor for controlling the damper, a valve for con-

trolling the motor, means for controlling the valve, comprising two pressure motors, one of said motors being actuated by variations in steam pressure discharged by said 5 boiler, and the other motor being actuated by variations in gas pressure discharged by said furnace.

3. In a regulator for controlling combustion in a boiler furnace comprising a 10 motor for regulating the discharge of gases from said furnace from steam pressure generated by said boiler, means for varying the movement of said motor from variations in the rate of combustion independent of 15 the steam actuating means, and means for compensating the movement of said motor

from variations in flue gas pressure caused by the movement of said motor.

4. In combination with a flue damper for controlling the discharge of gases from a 20 boiler furnace, a motor for primarily actuating said damper from variations in steam pressure generated by said boiler, means to vary the movement of said motor from variations in the rate of combustion independent of 25 the steam actuating means, and means for compensating the movement of said motor from variations in flue gas pressure when said damper is moved from variations in steam pressure.

JAMES LEWIS KIMBALL.
